TREATMENT OF HYDROCARBON OILS

Harold C. Weber, Milton, Mass., assignor to Universal Oil Products Company, Chicago, Ill., a corporation of South Dakota

No Drawing. Application December 10, 1931
Serial No. 580,221

3 Claims. (Cl. 196—30)

This invention relates to the treatment of hydrocarbon oils and refers more particularly to the treatment of the lower boiling motor fuel fractions produced in the straight run distillation of crude petroleums or from cracking the heavier portions thereof.

More specifically the invention has reference to the method of treatment of such low boiling motor fuel fractions to reduce their total sulphur content, though other beneficial refining effects may be produced at the same time.

A limit has been placed on the total sulphur allowable in minor fuels for automobile engines owing to the tendency of sulphur compounds of certain types to corrode feed lines, carburetor parts, etc., and the tendency of these and other compounds to form traces of sulphuric acid when the fuel is burned in the engine, the acid leaking past the piston rings sufficiently to cause some corrosion of the crank case. Since the majority of present day gasoline specifications have set a limit of approximately one-tenth of one percent as the maximum sulphur allowance in motor fuel, and since many straight run gasolines and the majority of cracked gasolines contain sulphur in excess of this amount, it has been necessary to devise treatments to reduce the sulphur content below the allowable limit.

The relative proportions of highly unsaturated or gum-forming compounds and sulphur derivatives in cracked gasolines or naphthas produced from various charging stocks and under widely varying cracking plant operations makes the treatment of each individual distillate a special problem.

In some cases the problem may be primarily one of sulphur removal and in other cases, such as in the case of distillates resulting from the high temperature cracking of low sulphur charging stocks, the problem may be rather the removal of the highly unsaturated olefinic hydrocarbons.

It is usual to find in treatments for desulphurization that the sulphur content may be reduced to a certain point with comparative ease, after which reductions are effected with great difficulty owing to the form or combination of the remaining sulphur, which apparently is contained in heterocyclic compounds, such as thiophene. The present invention is concerned with an efficient method of reducing the sulphur content of cracked gasolines below the point usually attained by the present commercial treating processes, though the treatment may also be effectively applied to the removal of the more

easily reactive types of sulphur compounds such as free hydrogen sulphide, mercaptans, sulphur ethers, etc.

In one specific embodiment the invention comprises treatment of hydrocarbon oils in the presence of silver, an electro-positive metal and a solution of salts capable of producing hydroxyl and chloride ions.

It will be evident from the foregoing to those versed in the science of electro-chemistry that under the conditions disclosed the particles of silver and the electro-positive metals, which are preferably present in a finely divided condition, form an electric couple. The marked affinity of silver for sulphur results in the rapid dissociation of the sulphur compounds with the fixation of sulphur on the surface of the silver. The innumerable small cell units which constantly generate hydrogen ions then act upon the superficial layer of sulphide to form gaseous hydrogen sulphide and renew the surface of the silver for further action, so that the process of desulphurization may be made substantially continuous under properly regulated conditions.

Of the electro-positive metals which may be used to form electric couples with the silver particles it is preferred to use those which are relatively high in the electro-chemical series, and those which are capable of being readily produced in a finely divided condition. As metals meeting these requirements may be mentioned sodium, aluminum, zinc, cadmium, iron, etc.

As salts capable of giving hydroxyl ions may be mentioned the ordinary caustic alkalis, such as caustic soda, caustic potash, and the carbonates and bicarbonates of the alkali metals and ammonia. Chlorides on the same basis may be used to furnish chloride ions, whose essential function is to prevent the precipitation of hydroxides such as those of aluminum or iron, which precipitation removes the metal from the sphere of the reaction and eliminates it as one of the members of the electric couple.

The process of the invention may be applied to the desulphurizing of gasolines and to the light hydrocarbon distillates in a variety of ways. As one mode of operation finely divided silver may be produced on an inert carrier, such as pumice, by the common steps of impregnating the pumice particles with a solution of the nitrate of the metal, igniting the nitrate at a minimum temperature to produce the oxide, and reducing the oxide (also at a minimum temperature to preserve the activity of the reduced metal), and

protecting the reduced material from oxidizing influences until it is ready for use.

Similarly the electro-positive metals essential to the process may be separately produced in a finely comminuted state and the silver and electro-positive metals mixed in proper molecular proportions. To the mixture of metals a strong solution of sodium carbonate and sodium chloride may be added to form a slurry or mud and the mass added to a pressure vessel provided with a mechanical stirring device. The oil to be treated is then added to the autoclave and heated to the proper temperature for the desulphurizing reactions with concurrent vigorous agitation.

15 The hydrogen sulphide produced and other fixed gases may be released intermittently or continuously to keep the pressure within safe limits.

At the conclusion of the treating period the agitation may be stopped and the contents of the pressure vessel allowed to stratify, whereupon the upper layer of gasoline or naphtha may be removed and distilled in separate equipment, partly by its contained heat, to produce an endpoint product needing only caustic washing to remove traces of dissolved hydrogen sulphide.

20 The treating mass remaining in the pressure vessel may be used without further additions of metals or salts until its efficiency drops below an economical point, whereupon it may be renewed by well known chemical methods, involving water extraction of the mass to remove soluble salts and the further extraction by acids or alkalis of the metallic particles, and a repetition of the steps which produce them in the finely divided condition necessary for their effective electrochemical action.

25 Another mode of operation which is frequently convenient when dealing with vapors arising from fractionators of crude stills or a cracking plant is to pass the vapors in a continuous stream upwardly through the silver and electro-positive metals supported on the inert carriers countercurrent to the electrolyte salt solutions, concentration of the solutions and the temperature and pressure of operation being so regulated that there is at all times an aqueous electrolyte in contact with the metallic particles. To provide against the contingency of over-concentration of the solution with resultant precipitation of salts and possible clogging of the apparatus steam 30 may be introduced into the oil vapors undergoing treatment, the effect of this addition being to depress vaporization of the solvent.

35 Operators skilled in the art of treating hydrocarbons will be able to devise other forms of equipment adaptable for producing the results desired by the use of the process of the invention, and since the invention is not limited to any form of apparatus in which it may be conducted it will be unnecessary to suggest further types.

40 As an example of the results obtainable when employing the process of the invention to treat gasoline vapors from a cracking plant, a case involving the use of a Mid-Continent gas oil as charging stock to the cracking plant may be cited. The cracking plant may be provided with a fractionator of sufficient capacity to produce vapors of approximate gasoline boiling point range at a pressure of 75 pounds per square inch 45 and a top tower temperature of 400° F., which temperature corresponds roughly to the end boiling point of the finished gasoline. The gasoline produced without chemical treatment of the vapors in such a case may have the properties 50 shown in the first column of the appended tabula-

tion, these properties being shown in comparison with those of a gasoline made by interposing the treating step characteristic of the present invention as one stage in the fractionation of the gasoline. The details of the operation may be essentially those already described in connection with vapor phase treatment, the solutions of mixed sodium bicarbonate and chloride being substantially saturated under the conditions of operation and used at the rate of 10 pounds of solution per barrel of condensed gasoline.

	Untreated gasoline	Treated gasoline	90
Gravity ° A. P. I.....	54.5	54.8	
Endpoint °F.....	405	406	
Color (Saybolt).....	8	+30

Gums by copper dish.....	350 mgs.	35 mgs.	
Total sulphur.....	0.3	0.04	
			95

It may be possible to utilize the mixture of silver and aluminum continuously until an amount of gasoline equal to 10,000 barrels per ton of metal mixture has passed through the treater before any revivification is necessary to maintain the efficiency of the process.

100 As another example of results obtainable, a pressure distillate produced by cracking a California residuum may be treated by the batch method, as described in the specification. By using approximately double the amount of electrolyte (that is 20 pounds per barrel) that was used in the first example and treating for 15 to 20 minutes at a temperature of 300° F. and a pressure of 200 pounds per square inch, the pressure distillate may be redistilled to produce a finished gasoline needing only a light caustic wash to render it in a stable and marketable condition. The tabulation following again shows the relative properties of the gasoline produced by simple fractionation of the pressure distillate and that produced by fractionation of the treated distillate:

	Untreated gasoline	Treated gasoline	110
Gravity ° A. P. I.....	53	53.3	
Endpoint °F.....	415	420	
Color (Saybolt).....	4	30	
Color after 4 hrs. exposure to sunlight.....		26	
Gums by copper dish.....	450 mgs.	50 mgs.	
Total sulphur.....	0.42	0.08	
			125

120 It will be evident from the foregoing description of the invention and the examples of results obtainable by its use that the present invention furnishes an entirely practical and highly efficient method for the treatment of cracked distillates. However, since many other examples of operation and results might be given, and since the 130 process is also well adapted to the treatment of straight run distillates to produce results substantially equivalent to those given in the examples of use on cracked distillates, it is not intended that the foregoing specification shall act in a 140 limiting sense upon the broad scope of the invention.

I claim as my invention:

1. A process for the refining of hydrocarbon distillates to desulphurize the same comprising subjecting the distillates to the simultaneous action of substances capable of producing hydroxyl ions and chloride ions while in the presence of metallic silver and metal electropositive to hydrogen.

2. A process for the refining of hydrocarbon distillates to desulphurize the same comprising subjecting the distillates to the simultaneous action of aqueous solutions of sodium bicarbonate and sodium chloride while in the presence of metallic silver and metal electro-positive to hydrogen.

3. A process for the refining of hydrocarbon distillates to desulphurize the same comprising subjecting the distillates to the simultaneous action of aqueous solutions of sodium bicarbonate and sodium chloride while in the presence of metallic silver, and aluminum.
